UNITED STATES PATENT OFFICE.

EDWIN S. MATTHEWS, OF NEW YORK, N. Y., ASSIGNOR TO OTIS ELEVATOR COMPANY,
OF JERSEY CITY, NEW JERSEY, A CORPORATION OF NEW JERSEY.

ELEVATOR.

1,109,853.

Specification of Letters Patent.

Patented Sept. 8, 1914.

Application filed May 26, 1911. Serial No. 629,652.

To all whom it may concern:

Be it known that I, EDWIN S. MATTHEWS, a citizen of the United States, residing at New York, in the county of New York and 5 State of New York, have invented a new and useful Improvement in Elevators, of which the following is a specification.

My invention relates to elevators and their operation; particularly to means for controlling them as they are started and stopped by an operator in the car.

An object of this invention is to automatically insure a smooth and determinate stop, and, if desired, a start in a reversed 15 direction without shock or jar to the wiring mechanism, the elevator car or its passengers, strain or disarrangement of the controlling mechanism or motive apparatus, independent of the type of elevator machine 20 employed or the kind of motive power utilized thereby.

By the use of this invention the operator in making a stop, however careless he may be, is automatically compelled to permit the 25 car to come to rest or nearly to rest by the means provided in the apparatus for retarding and stopping the car, before he can apply the force for reversing its motion; as will be hereinafter shown in the description 30 of this illustration of my invention and its mode of operation.

A further object of this invention is to accomplish this result positively and directly by utilizing the state of motion or rest of 35 the car itself as a means of automatically securing proper control of the apparatus instead of relying upon the functions of subordinate portions of such apparatus in a secondary manner as has been heretofore 40 done in the art; as where portions of valves, electric controllers, and other secondary mechanisms have been more or less successfully used to accomplish this purpose, in which cases these secondary mechanisms are 45 necessarily merely indirectly related in their operation to the state of motion or rest of the car.

Other objects of the invention will be now fully set forth hereinafter.

50 An embodiment of this invention is herein shown as applied to a hydraulic plunger elevator (although it is not limited to such an application) the construction and mode of operation of which as illustrated in the 55 accompanying drawings will be hereinafter

fully set forth in connection with this invention the substance of which is finally pointed out in the appended claims.

In the accompanying drawings, Figure 1 shows my invention in elevation applied to 60 a hydraulic plunger elevator and located under the elevator car; Fig. 2 is a detail plan view of certain parts under the car in Fig. 1; Fig. 3 is an illustration of my invention with essential parts thereof located 65 apart from the car.

Referring more specifically to Fig. 1, an ordinary type of hydraulic plunger elevator is shown in which the car C, counterweight W, plunger P, car controlling lever K, pilot 70 valve X and main valve V are well known parts with a well known and obvious method of operation.

A supply pipe 12, and a discharge pipe 11 connect the apparatus with a source of 75 water under pressure for supply and any suitable receptacle for exhaust of the fluid.

The apparatus is shown in a stopped position with the car at rest, with closed main and pilot valves. A lever 13 has the valve 80 stems 14 and 15 of the main and pilot valves respectively, pivotally connected to it, while the link 16 is pivoted to the end thereof. The control rope 17 is secured to the segment 18 and passes around the pulleys 19 of 85 the car controlling lever K in such a manner that the movement of this lever will produce a corresponding movement of the segment 18. One end of the rod 20 is rigidly secured to the segment 18 and its other end 90 is jointed to the link 16. A movement of the car controlling lever K by the operator thus causes a motion of the pilot valve through its stem 15 either upward or downward from its central position according to the direction (either toward the right or the left) of the movement imparted to the upward branch of the T-shaped car controlling lever K by the operator; this in turn causes the main valve V to be moved by the water pressure (either upward or downward as the case may be) either admitting pressure under the plunger and causing ascent of the car or allowing the water to be discharged

from beneath the plunger P and causing its descent; while the pilot valve is returned to its center or closed position by the motion of the main valve itself acting by its stem 14, at one end of the lever 13 upon the pilot valve through its stem 15 at an intermediate 105 110

point of the lever 13 while the other end of the lever 13 is held stationary in its up or down position by the link 16 as it has been moved by the operator in the car. The pilot 5 valve is thus set in position so that a movement of the car controlling lever back to the center moving the pilot valve, will cause the main valve to close and bring the car to rest irrespective of whether the motion of 10 the car has been that of ascent or descent, and when the car controlling lever is in center position and the main valve is closed as shown in the drawings, the pilot valve is again centered and closed by the closing 15 movement of the main valve and also appears as shown in the drawings with the entire apparatus at rest.

In the case of an elevator unprovided with my invention, a careless operator, particularly if he thinks he is liable to overrun a landing, frequently throws his controlling member in the car beyond the stopping point and in some cases carries it to the point of full speed reversal. In a plunger or a 20 hydraulic elevator this may bring the valve into a position of stoppage and even of reversal before the momentum of the moving parts has been properly checked or arrested causing violent shock, water hammer and 25 breakage of parts, while with electric elevators blowing of fuses and burning out of armatures may in some cases arise from such careless manipulation; while harmful results also follow in case of steam direct or 30 belt or brake retarded elevators as is known to those skilled in the art. The manner in which such undesirable manipulation of an elevator controlling mechanism is automatically prevented by my invention will be 35 obvious from a further inspection of the drawings and the following explanation of its method of operation.

A governor rope 21 extends from the top to the bottom of the hatchway, passing about 40 the governor pulley 22 and the idler pulley 23. Governor pulley 22 is mounted upon the shaft 24, as is also the flyball device 25 (Fig. 2). A lever 26 pivoted on the car C, has one end in connection with the sliding 45 end piece 27 of the device 25, and as the motion of the car causes the balls thereof to fly outwardly the lever 26 is rocked accordingly. At the other end of the lever 26 is a projection 28 designed to engage in the slot 50 29 of the segment 30 which is secured to the hand lever K. This slot is so located that the projection engages in it only when the hand lever is in its central position. It is evident that if the hand lever K is moved 55 over to one side and the car has attained a predetermined speed, the lever can not be moved past the central position in the opposite direction without the projection 28 engaging in slot 29, thus preventing the reversal 60 of the lever and of the valves until 65

the elevator car has slowed down to a prescribed speed. The governor device may be so adjusted that the projection will not be drawn out of the slot until the elevator car comes to a full stop, but the usual practice 70 is to have it so adjusted that the projection 28 is withdrawn from the slot 29 shortly before the car comes to a full stop.

In the modification shown by Fig. 3, the governor device is shown at the bottom of the hoistway; the type of elevator and controlling means is similar to that shown by Fig. 1. The control rope 17' in this case, is secured to the sheave 31, so that the movement of the lever K' in the car effects a 75 corresponding rotative movement of the sheave about the pivot 32. Rigidly attached to the sheave is the rod 20' which effects the actuation of the pilot valve X and the main valve V in a manner similar to that 80 previously set forth. The sheave wheel 31 is formed with an enlarged portion in which there is a slot 33. This slot is adapted to receive the projection 34 of the lever 35. The governor rope 21' passes around the enlarged grooved rim of the bevel gear 40 which meshes with a corresponding bevel gear 41 on the governor shaft 42. When the motion of the car causes the fly balls of the governor device 36 to fly outward they raise 85 the lever 38, rod 37, and the lever 35, causing the projection 34 to enter the slot 33 which locks the sheave 31 in the central position whenever the operator in the elevator car attempts to reverse the lever K' 90 from one running position past the center to a reversed running position while the car is in too rapid motion.

It is believed that my invention is clearly set forth in the foregoing description, although it is evident that those skilled in the art to which this invention appertains may make various changes without departing 95 from the spirit and scope thereof.

By this device an elevator is automatically protected from all injurious effects caused by improper co-relation of its stopping starting and reversing functions caused by careless manipulation of its controlling 100 apparatus.

What I claim and desire to secure by Letters Patent of the United States is:—

1. In elevator apparatus, the combination of a car, motive means for the car, a controlling member in the car, means to prevent the reversal of the controlling member when the car is moving above a predetermined speed, and a mechanical speed governor controlled by the motion of the car connected to operate and control said reversal preventive means.

2. In an elevator, the combination of a car, motive means therefor, a controlling device in the car, and a centrifugal safety governor operable to prevent the reversal of the 105 110 115 120 125 130

controlling means when the car is traveling at more than a predetermined speed.

3. In a hydraulic elevator, the combination of a car, a controlling device for the car, means to prevent the reversal of the controlling device when the car is moving above a predetermined speed, and a mechanical safety governor operated by the car and controlling said means.
- 10 4. In an elevator, the combination of a car, motive means for the car, a lever in the car for governing the motive means, and a speed governor operated by the car and arranged to prevent the lever from passing its central position when the car is moving in the direction corresponding with the position of the lever on either side of its central position.

15 5. In an elevator, the combination of a car, motive means therefor, a lever in the car to govern the motive means, and a centrifugal speed governor operable to prevent the reversal of the lever when the elevator car is moving too fast.

20 6. In an elevator, the combination of a car, motive means for the car, a lever in the car to control the motive means, a speed governor operated by the car, and a locking device operated by said governor to prevent 25 the reversal of the controlling lever when the elevator car is moving above a predetermined speed.

7. In an elevator, the combination of a car, motive means therefor, a controlling lever in the elevator car, a slotted segment attached to the said lever, a lever having a

projection adapted to engage in the slot, and a speed governor connected to said lever and holding said projection in contact with the segment to prevent the controlling lever 40 from being moved past its central position when it has been moved to a running position until the elevator car reaches a predetermined slow down speed.

8. In an elevator, the combination of a car, motive means therefor, a controlling lever in the elevator car, a slotted segment attached to the said lever, a lever having a projection adapted to engage in the slot, and a centrifugal speed governor dependent 50 for operation upon the movement of the elevator car and operative to prevent the movement of the controlling lever from a running position thereof past the central position until the elevator car reaches a cer- 55 tain slow down speed.

9. In a hydraulic elevator, the combination of a car, of main and pilot valves, means in the elevator car to control the valves, and a governor device operated by the car as it moves to prevent the reversal of the controlling means in the valves until the car has reached a predetermined and safe slow down speed.

In testimony whereof, I have signed my name to this specification in the presence of two subscribing witnesses.

EDWIN S. MATTHEWS.
